UNITED STATES PATENT OFFICE.

THOMAS JOSEPH STURTEVANT, OF WELLESLEY, MASSACHUSETTS, ASSIGNOR TO
STURTEVANT MILL COMPANY, A CORPORATION OF MAINE.

SCREEN OR SEPARATOR.

1,116,512.

Specification of Letters Patent. Patented Nov. 10, 1914.

Application filed May 21, 1914. Serial No. 340,071.

To all whom it may concern:

Be it known that I, THOMAS J. STURTEVANT, a citizen of the United States, residing at Wellesley, in the county of Norfolk and State of Massachusetts, have invented or discovered certain new and useful Improvements in Screens or Separators, of which the following is a specification, reference being had therein to the accompanying drawings.

This invention relates to that class of screens or separators more particularly intended for use in sifting very fine material and in which the screens or screen frames are vibrated by percussive action, and the invention relates to certain improvements by which the convenience and efficiency of the separator are augmented, as will hereinafter fully appear.

In the accompanying drawings, Figure 1 is an elevation of the improved separator. Fig. 2 is a side view, and Fig. 3 a vertical section of the same. Fig. 4 shows one of the screen frames in plan, side and end views, and Fig. 5 is an enlarged transverse section to show the manner in which the screen frames are supported.

Referring to the drawings, 12 denotes a suitable inclined frame or casing at the upper end of which is mounted a feeding chamber housing or casing 13, within which is journaled a rotating screw conveyer 14 carried by a shaft 15 provided with a driving pulley 16, the said casing part supporting a hopper 17 from which the material to be screened is fed into the trough or receptacle in which the said screw conveyer rotates, and which distributes the material laterally in said trough. These features of the machine are, or may be, the same as the machines now in use, and certain features of which are shown, for example, in U. S. Patent No. 923,108, excepting that in the present construction the housing or casing 13, forming the feeding chamber, is divided horizontally in a plane at or about the center line of the conveyer shaft 15 so that the upper part 13^a of the housing, which is attached by bolts 41 or otherwise to the lower part, may be removed to afford convenient

access to the feed regulating plate 42, or other parts, and the said upper part of said housing is provided with a hinged top or cover 43 which may be lifted when ready access to said feeding chamber is desired. 55

Within the casing or housing 12, and secured to the side walls thereof, are inclined longitudinal supporting bars 18 and inner inclined longitudinal supporting bars 19. The screens proper consist of comparatively 60 light and easily handled screen frames 20 on which the wire mesh screen clothing 21 is tightly stretched, and to which it is suitably secured, as by being riveted thereto. In the construction herein illustrated two 65 sets, one above the other, of these screens, supported at their inner edges on the inner supporting bars 19, are shown, but a larger number of these screens and additional inner supports 18, 19, may be provided for 70 large size separators; or, if it be desired, these screens may be made smaller or narrower for convenience in handling. The screen frames 20 rest at their longitudinal edges on the supports 18 and 19, and are removably attached to the inner supports 19 by buttons 22 and bolts 23. In the form of the invention herein illustrated two sets of 75 screens proper, one above the other, are shown, but it will be understood that three or more sets of screens may be employed, if desired. From this it will be understood that each screen proper consists of a plurality of framed screens, or framed screen sections 80 the edges of which rest on inner and outer longitudinal supports to which said framed screens are removably attached, so that the framed screen sections may be conveniently placed in or removed from their working 85 positions. 90

In the separators of the kind to which this invention more particularly relates, heretofore generally in use, and embodying percussively vibrated screens, the impact bars or hammer posts pass through all of the 95 screens except the bottom ones and also through the covers or tops of the screening chambers, causing leakage of dust between the screens and up through the covers. This objection is obviated in the present novel 100

construction which comprises compound anvil blocks, consisting of upper parts 24 resting on the upper inner supports 19, and lower parts 25 interposed between the upper 5 and lower inner supports 19, these anvil parts or blocks being held in flanged collars 25' rigidly secured to the said inner supports 19 by bolts 26 passing through the flanges of said collars and through clamping 10 blocks 27 and 28 between which are gripped transverse supporting cross bars 29 which sustain and brace the inner supports 19, and which, to a considerable extent, receive the percussive shocks imparted to the anvil 15 blocks by the vibrating hammers 30. These hammers 30 are preferably in the form of bell-crank levers, and are pivoted in brackets 31 sustained on the cover 32 of the separator, said cover being preferably provided with a 20 hinged joint 33 at its upper end so that it may be lifted, when desired, as when the removably mounted screens are to be inserted or taken out. The said cover 32 supports rotating shafts 34 provided with driving pulleys 35 and carrying at their inner ends rotating arms 36 provided with rollers 37 adapted to engage the upturned portions of the bell-crank hammers 30 for the purpose of lifting the same, said hammers falling 25 by gravity on the anvil blocks 24 when their upturned arms escape from the operating 30 rollers 37.

The hammer-operating arms are covered by hinged hoods 38 which prevent escape 35 of dust through the cover 32, but which may be lifted when access to the said arms is necessary. It will thus be understood that the anvil blocks or hammer posts do not pass through the screens, as in the former construction referred to, and as the vibrating 40 hammers 30 are mounted in the screening chamber no openings in the top or cover of said chamber, for the passage of hammer posts, are required. In other words 45 the jarring devices are inclosed in the screening chamber in the present improved separator. The cover 32 is supplemented at its lower end by a smaller hinged cover 39 which closes the top of the lower part of 50 the chamber of the separator. Access to the screening chamber from the back of the separator is afforded by a door 40 which is hinged at its top end to the frame of the separator.

55 From the foregoing it will be understood that the screens are supported by the longitudinal side bars 18 and the longitudinal inner bars 19, the latter being in turn sustained by the upper and lower transverse 60 bars 29; and while the screens are thus, in a sense, unyielding, in that they do not rest on springs, they are so supported that they will be percussively jarred, in the screening 65 operation, by the impact of the hammers.

mers 30 against the compound anvil blocks 65 comprising the parts 24 and 25. In other words, the screen supports themselves are hammer-vibrated by the impact of the ham-

mers. Owing to the fact that the framed screens 70 or screen sections rest at their inner edges on the resilient or elastic inclined longitudinal supports 19 which are between two adjacent framed screens and to which the anvil blocks are secured, and which elastic longitudinal supports are sustained between their ends by resilient or elastic transverse bars 29, the percussive impact of the hammers on the anvil blocks, which are preferably disposed in the vertical plane of 80 both of said longitudinal and transverse bars, will agitate the inner edges of said screens most violently, or will impart maximum vibrations to the inner edges of the screens, the outer edges of which rest on 85 the rigid or non-resilient longitudinal supports 18 on the separator frame. This action results in such side waves of movement of the screen clothing as will cause the material traveling down the screens to be 90 driven more or less crosswise of the screens; and thus the material will travel downward in a more or less zig-zag course, thereby securing a very effective and rapid 95 screening operation.

The lower parts 25 of the compound anvils not only serve to communicate the impact of the hammers from the upper parts thereof to the lower screens, but also serve as spacing blocks for the inner supports 19, 100 these supports 19 and transverse bars 29 constituting, when the machine is in operation, what may be termed a hammer-operated vibrating frame for communicating 105 jarring movements to the screens.

Having thus described my invention I claim and desire to secure by Letters Patent:

1. In a separator, the combination with removable, inclined framed screens comprising wire mesh clothing, of one or more resilient longitudinal supports for said screens, and means for percussively jarring said supports.

2. In a separator, the combination with 115 a plurality of resilient longitudinal screen supports, one above the other, of resilient transverse bars sustaining said longitudinal bars, and inclined framed screens removably mounted on said longitudinal supports and 120 comprising wire mesh clothing, and means for percussively jarring said resilient supports.

3. In a separator, the combination with a plurality of inclined resilient longitudinal supports, one above the other, of screen frames removably mounted on said supports and provided with wire mesh cloth-

ing, means for percussively jarring said resilient supports, and means for removably attaching said screen frames to said supports.

5. 4. In a separator, the combination with a casing or housing providing an inclosed screening chamber, of resilient longitudinal inclined screen supports in said chamber, screen frames removably mounted on said supports, vibrating hammers mounted in said screening chamber above said screen frames, and anvil blocks attached to said inclined resilient supports and on which anvil blocks said hammers operate for the purpose of jarring the screens.

10. 5. In a separator, the combination with a casing or housing providing an inclosed screening chamber, of a plurality of resilient inclined longitudinal supports, one above the other, in said chamber, framed screens mounted on said supports, anvil blocks made in sections the lower parts of which serve to space said supports, and vibrating hammers mounted within said chamber above said screens, and acting on said anvil blocks, for percussively jarring said screens.

20. 6. In a separator, the combination with a casing or housing providing an inclosed screening chamber, of a plurality of resilient inclined screen supports, one above the other, in said chamber, framed screens removably mounted on said resilient supports, anvil blocks secured to said supports and made in sections, vibrating hammers mounted within said chamber and acting on said anvil blocks, for percussively jarring said screens, resilient transverse supporting bars for said longitudinal screen supports, and means for clamping said resilient bars and supports together.

30. 7. In a separator, the combination with a casing or housing providing a screening chamber, inclined framed screens mounted in said chamber, one or more resilient longitudinal screen supports in said chamber and on which the inner edges of the screen frames rest, and jarring devices for said resilient supports, whereby the inner edges of the inclined screens will be most violently agitated.

40. 8. In a separator, the combination with a casing providing a screening chamber, of inclined, framed screens mounted in said chamber, longitudinal rigid supports on the separator frame for the outer edges of the screen frames, one or more resilient longitudinal screen supports, in said chamber, on which resilient support or supports the inner edges of the screen frames rest, and means for percussively jarring said resilient supports, and thus imparting maximum vibrations to the inner edges of said screens.

50. 9. In a separator, the combination with

a casing providing an inclosed screening chamber, of inclined framed screens mounted in said chamber, anvil blocks and hammers to act on said blocks, for percussively jarring said screens, also mounted in said chamber, said hammers being arranged above said screens, and resilient inclined supports to which said screens are removably attached and to which said anvil blocks are secured.

60. 10. In a separator, the combination with a casing providing an inclosed screening chamber, of inclined screens mounted in said chamber, anvil blocks and hammers to act on said blocks, for percussively jarring said screens, also mounted in said chamber, and resilient supports to which said screens are removably attached, said anvil blocks being secured to said supports and made in sections parts of which are interposed between said supports.

85

70. 11. In a separator, the combination with a casing or housing providing a screening chamber, of inclined screens mounted in said chamber, anvil blocks for jarring said screens, a movable cover for the said chamber, hammers to act on said anvil blocks, for percussively jarring said screens, said hammers being supported from said cover, hammer operating means mounted on the said cover so that the said hammers and their operating devices may be moved out of the way with said cover when access to the screening chamber is desired.

80. 12. In a separator, the combination with a casing or housing providing a screening chamber, of inclined screens mounted in said chamber, anvil blocks for jarring said screens, a hinged cover for the said chamber, hammers to act on said anvil blocks, for percussively jarring said screens, said hammers being supported from said cover, hammer operating means mounted on the said cover so that the said hammers and their operating devices may be lifted out of the way with said cover when access to the screening chamber is desired.

90. 13. In a separator, the combination with a suitable casing providing a screening chamber, of screening means in said chamber, a casing or housing mounted at the top of said screening chamber and providing a feeding chamber, a feeding member in said feeding chamber, for feeding material to said screening means, and a shaft by which said conveyer is carried, said feeding chamber or housing being divided horizontally in a plane at or about the center line of said shaft, and the upper part of said housing being removably attached to the lower part thereof.

125

100. 14. In a separator, the combination with a suitable casing providing a screening chamber, of screening means in said chamber,

4
ber, a casing or housing mounted at the top of said screening chamber and providing a feeding chamber, a feeding member in said feeding chamber, for feeding material to said screening means, and a shaft by which said conveyer is carried, said feeding chamber or housing being divided horizontally in a plane at or about the center line of said shaft, and the upper part of said housing

being removably attached to the lower part thereof and provided with a hinged cover.

In testimony whereof I affix my signature, in presence of two witnesses.

THOMAS JOSEPH STURTEVANT.
